CAP AND HANGER FOR CLEANING
IMPLEMENT

Glenn G. Greene, Jr., Warren, Pa.

Application October 28, 1949, Serial No. 124,198

1 Claim. (Cl. 248—359)

1

The present invention relates to brooms, brushes, mops and other cleaning implements of the types usually used in households, and it relates more especially to those having a tubular metal handle.

Cleaning implements of this type are now being provided largely with tubular metal handles instead of wooden handles as previously used generally; but one of the objections to the tubular handles has been the open end and exposed edge at the top of the handle as compared with the rounded upper end as provided on the wooden handles. Efforts have been made to obviate this objection by providing the upper end of the tubular handle with a cap composed of plastic, rubber or similar material, but such caps are fragile and liable to be easily detached from the end of the handle, and have been otherwise not satisfactory.

A primary object of the present invention is to provide a cap which may be produced with facility and inexpensively, and which may be readily attached securely to the top of the handle to close the end thereof and cover its upper edge, and which presents a neat appearance.

Another object is to provide such a cap which carries a hanging ring by means of which the implement may be hung on a nail or other projection on a wall or other support while the implement is not in use.

Another object of the invention is to provide a cap for closing the top of a tubular handle which carries a hanging ring adapted to be snapped down onto the cap where it is retained yieldingly while the implement is being used, and which may be readily extended from the top of the cap for engagement with a nail or other projection for hanging up the implement while it is not in use.

In the accompanying drawing, which illustrates the preferred embodiment of the invention applied for example, to a brush or similar household implement—

Figure 1 is an elevation of the implement having a tubular handle provided with a cap closing its upper end and provided with a hanging ring, the ring being extended from the cap and the implement hung thereby on a wall or other suitable support.

Figure 2 is an enlarged elevation of the upper end of the tubular handle provided with a cap and hanging ring according to the present invention, the hanging ring being shown in its folded position on top of the cap, as while the implement is in use.

2

Figure 3 is a top plan view of Figure 2.

Figure 4 is a vertical section on the line 4—4 in Figure 3, showing the hanging ring folded down on the top of the cap in full lines, and extended from the cap for hanging by the dotted lines.

Figure 5 is a detail plan view of the hanging ring.

Figure 6 is a detail enlarged section on the line 6—6 in Figure 3.

Similar parts are designated by the same reference numerals in the different views.

The broom or brush 10 to which the invention is shown applied in the present instance is provided with a tubular metal handle 11 the lower end of which is suitably attached to the back or body of the broom or brush, the upper end of the tubular handle being closed by the cap 12 provided according to the present invention.

The cap 12 is formed with a closed top 13 which is preferably flat or substantially so, a cylindrical lower portion 14 of a diameter to have a press fit into the open upper end of the handle, and an upper portion 15 which is preferably cylindrical and enlarged relatively to the portion 14 to overhang the upper edge of the handle when the cap is applied thereto, the upper portion 15 being formed preferably of a diameter substantially equal to that of the handle so that when the cap is applied to the handle, this portion of the cap will overlie the upper edge of the handle, and thereby protect the hand of the user from cutting or injury thereby, and the portion 15 preferably forms substantially a continuation of the exterior surface of the handle and is flush therewith, thus avoiding a shoulder or other obstruction to the hand while the implement is in use. The cap may be readily drawn from sheet metal and pressed firmly into the top of the handle where it is permanently secured.

The present invention provides a hanging ring 20 on the cap which may be extended therefrom to provide means for hanging the implement on a wall or other support while not in use, and may be folded down on the cap while the implement is in use. The cap is preferably so formed that the hanging ring will be partially embedded or countersunk in the cap while the hanging ring is in its folded or inoperative position and thus provide a somewhat rounded edge around the upper peripheral edge of the cap. For this purpose, the top of the cap is formed around its upper peripheral edge with an annular recess or channel 21 of a depth and width to at least partially receive the ring when the latter is folded down onto the cap. This recess or channel extends around the periph-

eral edge of the cap except at one side thereof where a portion 22 of the cap is continued outwardly from the top 13 of the cap and in the plane thereof to the outer side of the portion 15 and then extended downwardly, the cap being cut at each side of this portion 22 to provide openings 23 to receive the ends of the ring 20 which is split. The ring 20 is formed of spring steel or other suitable resilient metal, and its split formation enables the ring to be expanded to spread apart its ends for insertion beneath the portion 22, the latter thus forming a hinge strap which permits pivotal movement of the ring about its ends as a center whereby the ring may swing into the annular recess or channel 21 and thus occupy a folded relation with the cap, as shown by the full lines in Fig. 4, or it may be swung out of the recess or channel into extended position substantially at a right angle to the plane of the top of the cap, as shown by the dotted lines in said figure. The hinge portion 22 is preferably provided with an indentation 24 which occupies a position between the ends of the split ring, as shown in Fig. 6, thereby providing means for preventing displacement of either end of the ring from the hinge portion 22.

In order to yieldingly retain the ring in folded position on the cap and thereby prevent displacement thereof from its recess or channel due to motion of the implement incident to its use, the inner annular wall 25 of the recess or channel is formed of substantially cylindrical shape or provided with a slight overhang, and is of slightly greater diameter than the internal diameter of the ring 20 when the latter is contracted under its inherent resilience. Consequently, when the ring is swung into its folded position on the cap, the ring will be slightly expanded, and as the ring snaps into the recess or channel, it will be yieldingly retained therein. The ring may, however, be readily released from its recess and swung upwardly into extended position above the cap, by first inserting a thumb or finger nail between the bottom of the ring and the bottom of the recess or channel.

The formation of the cap with the portions 14 and 15 of different diameters produces a shoulder 26 between these portions which serves as an abutment to gauge the extent to which the cap is pressed into the end of the handle to frictionally secure it therein, this shoulder also overlying and shielding the upper edge of the handle from the hand of the user of the implement.

Caps provided by the present invention are durable and may be applied readily to tubular handles of implements of various kinds to close the ends thereof and shield their relatively sharp edges from the hands of the users of the implements. Since the caps may be made of sheet metal or other suitable light weight material, they may be manufactured inexpensively and readily applied to the tubular handles, and as the caps are secured to the handles frictionally when pressed therein, no rivets, screws or additional

securing means are required. The caps will not add appreciably to the weight of the implements to which they are applied, and they present a neat appearance.

The combined cap and hanging ring provided by the present invention enables the cap to be utilized as means for attaching the hanging ring to the handle, and the ring while seated in its annular recess or channel contributes to the formation of a rounded end on the handle. As the ring is yieldingly retained in folded position in the annular recess or channel in the cap while the implement is in use, it will not rattle or become displaced incident to the movements of the handle in manipulating the implement, although the ring may be easily and quickly extended from the cap for hanging up the implement on a wall or other suitable support while not in use.

1 claim:

A cap and hanger for application to a tubular handle, comprising a cap member having a cylindrical portion of a diameter to be pressed into and secured in an end of the handle and having another cylindrical portion of relatively greater diameter than that of said first-mentioned portion to overlie the edge of the end of the handle, said portion of greater diameter having a closed top and an annular recess surrounding it at the junction of its periphery with the periphery of said portion of greater diameter and having an annular inner wall, said annular recess and inner wall being contained within the diameter of said portion of greater diameter, and said top having a hinge portion which is cut therefrom and extends outwardly beyond said annular recess and inner wall, and a resilient hanging ring pivotally connected to the cap member by said hinge portion for swinging movement into the annular recess and having an inherent diameter less than that of said annular inner wall to frictionally retain the ring in folded relation with the cap member, or for swinging movement out of said recess and into extended relation with the cap member.
